UNITED STATES PATENT OFFICE.

ANDREW J. BRADLEY, OF NEW YORK, N. Y.

STEEL DIE-PUNCH.

1,118,181.

Specification of Letters Patent.

Patented Nov. 24, 1914.

Application filed April 2, 1914. Serial No. 829,908.

To all whom it may concern:

Be it known that I, ANDREW J. BRADLEY, a citizen of the United States, and a resident of the city of New York and State of New York, have invented a new and useful Improvement in Steel Die-Punches, of which the following is a specification.

This invention relates to steel dies and punches such as are used in stencil cutting machines, and comprises the dies described in my pending application Serial No. 778,889, for processes of making steel die punches.

Punches for stencil machines should have bodies with parallel walls exactly conforming to the shape of their faces. A punch body with parallel walls will not stretch the uncut paper surrounding the portions cut out thereby during the punching stroke, as might occur if the punch body was tapered toward the face of the punch, and also a parallel walled punch will not catch under the edges of the hole on the return stroke, as might occur if the punch body was upset 25 or enlarged upon its face.

Dies for stencil machines should be a few thousandths of an inch larger than the faces of the punches mating therewith and moreover, the opening through the side should 30 be flared or slightly enlarged toward the bottom of the die in order to provide a clearance for the punched out pieces of the stencil and allow them to fall through readily.

The object of this invention is a steel die 35 and punch having the characteristics hereinafter set forth, and what the invention consists in is more particularly defined in the appended claims.

In the accompanying drawings, in which 40 like characters are used to designate the same parts in the several views,—Figure 1 is a top plan view of the die blank from which both the punch and the die comprised in this invention are made; Fig. 2 is a cross-section 45 of the die blank on the line 2—2 in Fig. 1; Fig. 3 is an edge view of the die blank; Fig. 4 is a top plan view of the punch plate prior to assembling the punch pieces with it; Fig. 5 is a cross-section of the punch plate on 50 the line 5—5 in Fig. 4; Fig. 6 is a cross-section of the punch plate and die blank superposed prior to the welding operation. Fig. 7 is a view similar to Fig. 6 showing the punch plate and die blank after the 55 welding operation and prior to separating the punch pieces from the die blank; Fig. 8

is a cross section of the welded punch plate; Fig. 9 is a cross section of the die blank after the punch pieces have been separated therefrom; Fig. 10 is a bottom plan view of the 60 finished punch; Fig. 11 is a top plan view of the finished die; and Fig. 12 is a side elevation of the finished punch and die, showing the manner in which they are mounted in a stencil cutting machine.

In making punches and dies according to this invention it is necessary to have a full set of master punches and dies, comprising all the letters of the alphabet and the usual punctuation marks and characters, together 70 with the numeral figures 2 to 9, inclusive. The master dies are made with the character reversed in plan view, and the master punches and dies are very carefully fitted to each other, the clearance between their 75 co-operating cutting edges being not over one-thousandth of an inch. In addition to the letter or number character, the master punches have three pins which coöperate with three holes in the master dies for 80 punching three dowels or distance posts for positioning the die blank and punch plate at the proper distance apart in the process of making the punch.

The process followed in making the stencil punches and dies is as follows: A steel die blank 21, about three-sixteenths of an inch thick, is placed on the master die, and the punch is brought down until it has penetrated about four-fifths through the die 90 blank. This stroke is sufficient to completely sever the punchings 22 from the die blank, but will leave them sticking therein. At the same stroke the three pins in the master punch lining up with the holes in the master 95 die are forced partly through the die blank, but to a slightly less extent than the punchings, the lower ends of the pins being set slightly above the face of the punch. The outer ends of the posts 23 which are raised on the face of the die blank (the top face in Figs. 1 and 2) by the pins on the punch block are about one thirty-second of an inch short of the extremities of the punchings 22.

The top edges of the holes punched in the 105 die blank (the lower edges in Figs. 1 and 2) are left slightly rounded by the punch instead of having absolutely square corners. It is impossible to punch soft steel and get absolutely square corners on the top edges 110 of the punch holes due to the metal surrounding the hole flowing slightly under

the pressure brought upon it by the punch. Heretofore, in making stencil dies by master dies having the character cut upright instead of inverted, it has been necessary to 5 grind off the top surface of the die blank in order to get square corners for the cutting edges of the stencil die made therefrom. In this process, the square face of the die blank becomes the cutting face of the stencil die, and the rounded corners made by the 10 punch are of advantage in providing bottom clearance in the holes additional to that made by the tapered side walls of the punch. For a similar reason to that causing the top 15 edges of the holes to be slightly rounded, the projecting edges of the punchings 22 are slightly rounded. The punchings, however, have parallel walls exactly conforming in size to the holes in the master die through 20 which they are forced, instead of being tapered like the punch. The cutting edges of the holes in the die blank, on the other hand, are slightly smaller than the holes in the master die, due to slight contraction 25 after the withdrawal of the punch, and grip the punchings tightly.

The die blank 21 is laid face up, as shown in Fig. 6, and a punch plate 24 is placed on it, with the punched out holes 25 fitting the 30 punchings 22. The punch plate is made with the same master dies with which the die blank was formed, but without the punch pins, and the punch is forced entirely through the plate. The tapered punch 35 bevels the side walls of the holes 25 slightly, the holes being slightly wider on the side from which the punch approaches. This is the lower side of the punch plate, as shown in Figs. 4 and 5. The clearance between 40 the rounded edges of the holes in the punch plate and the rounded edges of the punchings 22 is sufficient to enable the two plates to be assembled one on the other as shown in Fig. 6, but not sufficient to leave any appreciable space between the meeting corners, 45 and accordingly the punch plate serves as a templet for assisting in maintaining the proper alinement of the punchings during the following operation. The posts 23 serve 50 to position the punch plate parallel with the die-blank and insure that the depth to which the punchings project into the holes in the punch plate shall be uniform.

The punch plate and die-blank are 55 clamped in assembled position, and molten steel of the same composition as the punch plate is poured or fused into the cavities in the latter over the punchings 22. This molten steel fuses the punchings to the punch 60 plate and forms a solid punch 26, as shown in Fig. 7. The operation is performed quickly, and the punch plate and die blank are so massive in proportion to the molten metal that they are not much distorted by 65 heat transferred to them during the opera-

tion. Moreover, if there is slight distortion of the punch plate it does not affect the alinement of the punchings, which are securely held by both the punch plate and die-blank. After the parts cool, the punch plate 70 and punchings are separated from the die-blank, and the surplus metal from the welding operation is planed or ground off from the back of the punch plate, which then appears as shown in Fig. 8.

The die-blank is placed on the master die and lined up by the pins 23. The master punch is forced through the die-blank to trim up the cutting edges and give a slight taper or relief to the sides of the holes, and 80 holes 27 are simultaneously punched for the screws 28 which attach it to the base plate 29 of the stencil cutting machine. The edges of the die-blank are trimmed up, the screw holes 27 are counter sunk on the top side, 85 and the die-blank is case hardened, forming the finished stencil die 30, as shown in Figs. 11 and 12.

The punch plate is trimmed around its edges and drilled with two holes 31 which 90 are counterbored on the side adjacent the punches for the screws 32 which secure the punch plate to the punch block 33 of the stencil cutting machine. After mounting the punch plate, the punch is forced through the hardened stencil die, which shaves off the edges of the punch walls to fit the cutting edges of the die exactly. The punch 95 may be left soft, if only paper stencils are to be cut.

It is to be noted that the above described process produces punches and dies having sharp cutting edges exactly conforming to each other without hand filing, and without grinding off the cutting faces; obviously, 105 the punch portions coöperating with the die are exact counterparts of the holes in the latter because both are made with the same master dies.

It is evident that the sizes, shapes and 110 thicknesses of the several parts, and the materials used, may be changed without affecting the process. It is also evident that the die-blank may be punched clear through at the first stroke of the dies and the punchings 115 reinserted therein or assembled in a separate templet for holding them properly during the operation of welding them to the punch plate. Moreover, the punchings may be secured to the punch plate by welding, brazing, soldering, or any other method 120 which will unite the parts in a secure manner.

This invention is not limited to the exact 125 number or sequence of operations described as constituting the preferred process of making my improved stencil dies. The process characterizes the dies forming this invention only in so far as set forth in the following claims.

What I claim as my invention is:

1. A stencil character punch consisting of a punch plate having portions removed therefrom forming openings conforming to said character, inverted punchings conforming to said character arranged in said openings and projecting below said punch plate, and means for securing said punchings in said openings.
  - 10 2. A stencil character punch consisting of a punch plate having portions removed therefrom forming openings conforming to said character, inverted punchings conforming to said character arranged in said openings and projecting below said punch plate, and a filling of fusible metal in said openings securing said punchings therein.
  - 15 3. A stencil character punch consisting of a metal punch plate having a considerable thickness, and punchings of the same metal and having the same thickness as said punch plate projecting into said punch plate and fused thereto.
  - 20 4. A stencil character punch and die comprising straight walled punch portions and tapering walled die portions, said portions
  - 25
- having their cutting edges composed of counterpart sections of a single piece of metal.
5. A stencil character punch and die comprising straight walled punch portions and tapering walled die portions, said portions having their cutting edges composed of the faces of counterpart sections of a single piece of flat metal.
  - 30 6. A stencil character punch and die consisting of a die having punched openings with their side walls diverging downwardly, a punch comprising a plate which is a replica of said die and punch portions which are counterparts of said openings projecting from the openings in said plate, said punch portions having straight side walls, and a filling of fusible metal in the openings in said plate behind said projecting punch portions.
  - 35

Signed at the city of New York, N. Y.,
this 28th day of March, 1914.

ANDREW J. BRADLEY.
